UNITED STATES PATENT OFFICE.

CORNELIUS EVAN JOHNSON, OF GRAND RAPIDS, MICHIGAN.

LOOSE-LEAF BINDER.

Application filed July 22, 1926. Serial No. 124,260.

The present invention relates to loose-leaf binders; and its object is to provide such a device having improved means for releasably securing together the leaf-binding members of the device; and further, to provide improved leaf-holding posts in such a binder; and further, to provide in such a device improved means for mounting the covers of the binder on the leaf-binding members thereof.

These and any other objects hereinafter appearing are attained by, and the invention finds preferable embodiment in, the loose-leaf binder hereinafter particularly described in the body of this specification and illustrated by the accompany drawings, in which:—

Figure 1 is a view in perspective of a loose-leaf binder;
20 Figure 2 is a view in perspective of a portion thereof, showing the cover in open position;

Figure 3 is a longitudinal sectional view of portions of the device taken on line 3—3
25 of Figures 1 and 2;

Figure 4 is a transverse sectional view thereof taken on line 4—4 of Figure 3;

Figure 5 is a view in perspective of an auxiliary leaf-binding member;

30 Figure 6 is a plan view of a portion of the device, showing one of the covers in open position, and exhibiting a locking device;

Figure 7 is a longitudinal sectional view
35 thereof taken on line 7—7 of Figures 6 and 8; and

Figure 8 is a plan view of the same, the lock's casing being sectioned on line 8—8 of Figure 7.

40 In the embodiment of the invention chosen for illustration by the accompanying drawings and for detailed description in the body of this specification, a loose-leaf binder is shown having a lower leaf-binding member

45 or element 1 carrying leaf-binding posts 2 extending through holes in the leaves or sheets of the binder's contents 12, and an upper leaf-binding member or element 3, said contents being held between said members or elements. The leaf-binding member 3 has openings 4 removably receiving the upper ends of the posts 2 which ends are provided with annular grooves or recesses 5. On the upper side of member 3 is mounted a bar 6 slidably bearing thereon, short headed studs 7 carried by said member ex-

tending through longitudinally disposed slots 8 in the bar. This bar is provided with longitudinally extending keyhole slots 9 having at one end enlarged portions 10 removably receiving the upper ends of the posts 2 in one slid position of the bar, and restricted or narrower portions 11 engaging in the grooves or recesses 5 of said posts in another slid position of the bar, seen in Figures 3 and 4, to hold the binding members 1 and 3 together.

A spring catch 13 is mounted on a short post or stud 14 carried by the member 3 and extending through a slot 15 in the bar 6. This spring catch is slidable in a bearing 16 formed by the laterally extending struck up portion 17 of the bar, which portion also forms a stop 18 against which the shoulder 19 of the spring engages to hold the bar in the position seen in Figures 3 and 4 in which the leaf-binding members 1 and 3 are securely held together. By pressing this spring catch by hand downwardly it may be released from the stop 18 whereupon the bar 6 may be slid manually to a position wherein the posts 2 may be withdrawn from the upper leaf-binding member 3.

In order to conceal and protect the upper ends of the posts 2, the keyhole slots 9 through which they pass are covered by outwardly spaced integral portions 20 of the bar 6 extending over these slots from end to end thereof.

The said portions 17 and 20 of the bar 6 are desirably formed by slitting the bar and bending said portions upwardly or outwardly.

Each of the posts 2 desirably comprises a sleeve member 21 having an inwardly extending bottom flange 22 and a second member 23 in the sleeve member and having a shoulder 24 engaging said flange and a shank portion 25 extending through the sleeve member's flanged lower end and through the lower leaf-binding member's opening 26 and being riveted at 27 on said member's under side to fasten said members 21 and 23 securely on the lower leaf-binding member 1. This second member 23 has also a reduced outer or upper portion 28 threaded as shown, on which adjustably turns the internally threaded extension member of the post 29 extending into the sleeve member 21. Either of the binder's covers 30, 30 is mounted on either leaf-binding member 1, 3 by means of a plate 31

having parallel portions 32, 33 and an intermediate portion 34 extending approximately at right angles to the parallel portions. The portion 32 is hinged at its outer edge, at 35, to the outer edge of the leaf-binding member and extends thence over the same, the other parallel portion 33 being fastened as by rivets 36 to the inner side of the cover. It will be seen that, by this construction, 10 the leaf-binding members or elements 1, 3 are covered and concealed, and the outer surfaces of the cover and of the parallel portion 32 may be disposed in substantially the same plane, thus providing a device of this 15 character having no projecting side parts.

As shown in the modification in Figures 6, 7 and 8, a lock for the device is provided. The upper leaf-binding member 3¹ has a laterally or upwardly extending lug 40, and 20 the bar 6¹ is provided with a longitudinally extending slot 41 in which the lug bears in the sliding movement of the bar. A locking bolt 42 is mounted in a casing 43 on the bar slidably in the bar's transverse direction. This bolt has a slot 44 through which the lug 40 extends, and a shoulder 45 against which the lug, spring-pressed at 46, engages in the position of the bar 6¹, seen 25 in Figure 8, in which the leaf-binding posts 30 are held by said bar. A key 47 may be inserted through the keyhole 48 in the casing and turned to move the shoulder 45 of the bolt from engagement with the lug 40 so that the bar 6¹ may be slid to a position 35 releasing the binding posts 2.

An auxiliary leaf-binding member 50 may be provided having openings 51 through which the leaf-binding posts 2 removably extend, and having adjustable leaf-binding 40 posts 2¹ similar in construction to posts 2 but extending downwardly.

The invention being intended to be pointed out in the claims, is not to be limited to or by details of construction of any particular embodiment thereof illustrated by the 45 drawings or hereinbefore described.

I claim:

1. In a loose-leaf binder: a leaf-binding member carrying a post whose outer end 50 is provided with a lateral recess; a second leaf-binding member having an opening removably receiving said end; a bar slidably bearing on said second member and provided with a longitudinally extending slot and a second longitudinally extending slot having an enlarged portion removably receiving said end in one slid position of the bar and

a restricted portion engaging in the recess to hold the post in the slot in another slid position of the bar; a spring catch mounted 60 on a post extending through the first-mentioned slot, the bar having a laterally extending portion provided with a bearing in which the catch slidably bears and a stop with which the catch engages to releasably hold the bar in its second-mentioned slid position.

2. In a loose-leaf binder: a leaf-binding member carrying a post whose outer end is provided with a lateral recess; a second leaf-binding member having an opening removably receiving said end; a bar slidably bearing on the said second member and provided with a longitudinally extending slot having an enlarged portion removably receiving 75 said end in one slid position of the bar and a restricted portion engaging in the recess to hold the post in the slot in another slid position of the bar, the bar having also an outwardly spaced portion extending over the 80 slot from end to end thereof; means for releasably holding the bar in its second-mentioned slid position.

3. In a loose-leaf binder: a pair of leaf-binding members; a pair of covers; means 85 for mounting either cover on either of said members comprising a plate having parallel portions and an angularly extending intermediate portion, one of said parallel portions being hinged at its outer edge to 90 the outer edge of said member and extending thereover, and the other of said parallel portions being fastened on the inner side of the cover.

4. In a loose-leaf binder: a leaf-binding 95 element having an opening therethrough; a binding post comprising; a sleeve member having an inwardly extending bottom flange; a second member therein having a shoulder engaging said flange and a portion extending through the sleeve member's flanged end and through said element's opening and riveted on said element's outer side, said second member having a reduced 100 threaded outer portion; an extension member of the post extending into the sleeve member and internally threaded on said second member's outer portion; a second leaf-binding element removably connected to the outer end of said extension member.

In testimony whereof I have hereunto set my hand at Grand Rapids, Michigan, this 27th day of May, 1926.

CORNELIUS EVAN JOHNSON.
